CLAIM

The ornamental design for an adjustable zip line pod, as shown.

DESCRIPTION

FIG. 1 is a perspective view of the adjustable zip line pod of the present invention, looking angularly towards a front edge thereof;

FIG. 2 is a perspective view of the adjustable zip line pod of the present invention looking angularly towards a rearward edge thereof;

FIG. 3 is a front elevational view of the adjustable zip line pod of the present invention;

FIG. 4 is a rear elevational view of the adjustable zip line pod of the present invention;

FIG. 5 is a left side elevational view of the adjustable zip line pod of the present invention;

FIG. 6 is a right side elevational view of the adjustable zip line pod of the present invention;

FIG. 7 is a top plan view of the adjustable zip line pod of the present invention; and,

FIG. 8 is a bottom plan view of the adjustable zip line pod of the present invention.

The dotted lines in the drawing show contour.

The broken lines in the drawing consisting of two short dashes and a long dash depict environmental subject matter only and form no part of the claimed design.
